(57) **CLAIM**

The ornamental design for a bread lame, as shown and described.

DESCRIPTION

FIG. 1 is a perspective view of a bread lame showing my new design;

FIG. 2 is an exploded perspective view of a bread lame;
FIG. 3 is an alternative perspective view of a bread lame with a blade;

FIG. 4 is a top view thereof;

FIG. 5 is a bottom view thereof;

FIG. 6 is a left side view thereof;

FIG. 7 is a right side view thereof;

FIG. 8 is a front view thereof; and,

FIG. 9 is a back view thereof.

The broken lines in the drawing depict environmental subject matter only and form no part of the claimed design.
